UNITED STATES PATENT OFFICE

2,509,778

CHAFF SEPARATOR

Maurice T. Moler, Chicago, Ill., assignor to United Specialties Company, Chicago, Ill., a corporation of Delaware

Application June 20, 1947, Serial No. 755,863

3 Claims. (Cl. 183—73)

1

This invention relates to a device for use in removing chaff or comparable material from a volume of air which is drawn into an enclosed space. It has for one object to provide a chaff separator or chaff screen for use in connection with air cleaners.

Another object is to provide a chaff separator which is self-cleaning.

Another object is to provide a chaff separator of such construction that chaff and comparable material will not be lodged or caught in the separator, and will be free to fall away when the speed of the column of air entering the device is reduced sufficiently.

Other objects will appear from time to time in the specification and claims.

The invention is illustrated more or less diagrammatically in the accompanying drawing in a figure which is a partial cross section through one form of the device with parts shown in section and parts shown in elevation.

Like parts are indicated by like characters in the specification and drawing.

As shown, the separator is mounted about an intake pipe 1 which may be connected to a carburetor or to a cleaner of any type. A spider 2 is provided with an outwardly flared or spaced portion 3 which is fitted about the upper end of the tube 1. A clamp 4 positioned about the spider portion 3 is effective to hold the parts together. The spider is provided with one or more openings 5 through which air may enter. The material of the spider is preferably upwardly bent about the margins of the openings as at 6. The spider terminates in a peripheral flange 7.

A dome 8 is positioned above the spider and is formed to provide an outwardly directed flange 9 which is positioned upon the flange 7. An inwardly bent integral portion 10 clamps the flange 7 of the spider.

The chaff separating member comprises a perforated, generally cylindrical member 11. The perforations in that member are indicated as at 12. A disc-like member 13, which is preferably not perforated, is provided with an upwardly extending peripheral flange 14 which is positioned about the separating member 11 and serves as a support for it. The member 11 may be permanently secured to the flange 14 by welding or otherwise, or may merely be fitted within it. Attached to or formed integrally with the member 13 is a tubular portion 15 of such size that it may fit over the tube 1. A clamp 16 holds the member 15, and consequently the member 13 and the cylindrical member which it supports, in the posi-

2

tion shown. The member 11 is thus held in place and its upper edge abuts against the bottom surface of the member 10.

Although I have shown an operative form of my invention, it will be recognized that many changes in the form, shape and arrangement of parts can be made without departing from the spirit of the invention, and my showing is therefore to be taken as, in a sense, diagrammatic.

10 The use and operation of this invention are as follows:

The device as shown is mounted upon a member through which a column of air or gas is to be drawn. One use of the device is in connection

15 with tractors which are to be driven through fields or used in an atmosphere in which chaff and comparable foreign material will be carried by the column of air. The perforations are of such size that chaff cannot pass through them,

20 and hence the chaff is filtered or separated from the air as it enters the perforations 12. The suction exerted by the air passing through these perforations may cause the chaff to adhere to the exterior of the member 11. The perforations

25 will not be clogged sufficiently to interfere with the passage of the air because of their large number. The device is thus effective in removing the chaff and comparable material from the entering column of air, and at the same time is not clogged to any important degree by the chaff.

When the volume of entering air is reduced to below a predetermined maximum, its suction is no longer effective to hold the chaff in place on the outside of the member 11. When that occurs,

35 the chaff merely falls to the ground or is blown away. The device is thus self-cleaning. If used on a tractor, pulling a harvester or combine or other implement through a field of grain or hay, the chaff will tend to accumulate on the exterior of the member 11 while the machine is driven

40 the length of one row, and when the engine is slowed down as the machine is turned to drive the next row, the flow of entering air is no longer sufficient to hold the chaff in place, and thus the chaff is freed and falls to the ground, or it blows away. The device is thus cleaned or cleared as

45 the result of variations in the conditions of use, which variations are necessary in the use of the machine on which the chaff separator is mounted. Where in the specification and claims the word "chaff" is used, it is to be understood as referring not merely to "chaff" but to foreign matter physically comparable to chaff. Fine dust is not

50 included in the meaning of this word and will

not be stopped by the device of the present invention.

I claim:

1. In combination in a chaff separator, a member defining an inlet passage, and a chaff separating member positioned outside of said inlet passage member in the path of entering air, said chaff separating member being provided with a smooth exterior and with a multiplicity of small openings, said openings being sufficiently large for fine dust to pass therethrough and sufficiently small to prevent the entrance of chaff, and an air impervious hood positioned above said inlet passage and joined to said separating member, and a flared extension joined to said inlet passage member and to said hood and engaging said separating member.

2. In combination in a chaff separator, means defining a vertically disposed inlet passage, and an upwardly and outward flared member secured adjacent the upper end of said passage, said outwardly flared member provided with a plurality of openings, and an air impervious, domed member secured to said flared member, an outwardly extending supporting means secured to said passage member and of substantially the same diameter as said outwardly flared member, a chaff separating means positioned upon said supporting member and extending upwardly to close the space between it and the flared member, said chaff separating means provided with a multiplicity of small openings therethrough, the exterior surface of said means being smooth.

3. In combination in a chaff separator, a down-

wardly directed, upwardly open air intake pipe, an outwardly flared perforated member fixed about the upper end of said pipe, an imperforate dome-shaped member fixed to the outer edge of said flared member and extending upwardly therefrom, and an imperforate generally flat member fixed to said pipe below said outwardly flared member and of substantially the same diameter as said member, and a cylindrical perforated smooth member positioned about said pipe beneath said flared member and above said generally flat member and held in place by said generally flat member, the diameter of said cylindrical member being approximately that of said flared member and said flat member.

MAURICE T. MOLER.
